US0D1079614S

(12) **United States Design Patent** (10) **Patent No.:** **US D1,079,614 S**
(45) **Date of Patent:** **** Jun. 17, 2025**

(54) **BATTERY CHARGING STATION**

(71) Applicant: **XYZ REALITY LIMITED**, London (GB)

(72) Inventors: **Guy Newsom**, London (GB); **Rupert Warries**, London (GB)

(73) Assignee: **XYZ REALITY LIMITED**, London (GB)

(**) Term: **15 Years**

(21) Appl. No.: **29/874,863**

(22) Filed: **Apr. 26, 2023**

(51) **LOC (15) Cl.** **13-02**

(52) **U.S. Cl.**

USPC **D13/107**

(57) **CLAIM**

The ornamental design for a battery charging station, as shown and described.

DESCRIPTION

FIG. 1 is a front view of the battery charging station when open;

FIG. 2 is a left side view of the battery charging station when closed;

FIG. 3 is perspective view of the left side and top of the battery charging station when closed;

FIG. 4 is perspective view of the right side and top of the battery charging station when closed;

FIG. 5 is a perspective view of the top of the battery charging station when open;

FIG. 6 is a rear view of the battery charging station when open;

FIG. 7 is a right side view of the battery charging station when closed; and,

FIG. 8 is a top view of the battery charging station when open.

The broken lines in FIGS. 1-8 show portions of the battery charging station that form no part of the claimed design.

1 Claim, 8 Drawing Sheets
